PACKER AND SETTING TOOL COMBINATION

Cicero C. Brown, Houston, Tex.

Application November 26, 1937, Serial No. 176,457

10 Claims. (Cl. 166—20)

This invention relates to a packer and setting tool combination for use in completing oil wells or the like.

The improvement relates to wells having screens or strainer pipes permitting entry into the well of fluids but preventing entry of sand and such materials as tend to clog the well and stop its flow. Equipment of that general character has frequently included a packer or other sealing device between the screen and the well tubing to assist in regulating the washing of the screen.

In the structures heretofore used, there has in many instances been no packer between the screen and tubing, and in instances where such a packer has been provided, it has been of such a nature that, once set, it could not be removed without being cut and fished out.

It is the general object of this invention to provide a novel screen, packer and setting tool combination, which will avoid certain disadvantages of similar prior combinations and provide advantages not heretofore obtainable.

It is an object of this invention to provide a screen, packer and setting tool combination in which no substantial flow can take place through the screen during the time it is being lowered into the well, or during the washing operation.

It is a further object to provide a combination of the type set forth in which a seal will be formed between the tubing and the upper end of the screen during the time that the screen is suspended from the tubing.

Another object is to provide a combination of the type set forth in which a packer is associated with a means for suspending the screen from the tubing in such a manner that, when such means is in operative position, the packer will be expanded to form a seal between the tubing and the upper end of the screen.

Another object is to provide a structure wherein in the packer adapted to form the seal between the screen and the casing cannot be accidentally set.

Another object of this invention is to provide a device which will automatically form a seal between the tubing and the upper end of the screen upon the forming of a seal between the upper end of the screen and the casing.

Another object is to provide a device for forming a permanent seal between the tubing and the upper end of the screen, which seal may be removed at will by simply an upward pull upon the tubing.

Another object is to provide a novel device for suspending a well screen, packer, etc., from a string of tubing.

One other object is to provide a novel type of setting tool for setting a well packer.

Other objects and advantages sought by this invention will become apparent from the following description, taken in connection with the accompanying drawings, it being clearly understood that said description and drawings are by way of illustration and example only, and not by way of limitation.

In the drawings:

Fig. 1 is a vertical cross section of the upper portion of a device constructed in accordance with this invention, the same being in position within the lower end of the well.

Fig. 2 is a vertical cross section of the lower portion of the device illustrated in Fig. 1, Fig. 2 constituting a continuation of the lower portion of Fig. 1.

Fig. 3 is a view illustrating the device shown in Fig. 1 after the tubing has been released from the strainer so that it may be raised with respect thereto, but prior to the formation of a seal between the upper end of the strainer and the casing.

Fig. 4 is a view partly in vertical cross section illustrating the device shown in Fig. 3 after the seal has been formed between the upper end of the strainer and the casing.

Fig. 5 is a top plan view of a circular spring element forming a part of the packer assembly shown in Figs. 1 to 4, inclusive.

Fig. 6 is an elevation of the same element.

Fig. 7 is a top plan view of the slip ring actuated by the element shown in Figs. 5 and 6.

Fig. 8 is a view partly in vertical cross section showing the slip ring illustrated in Fig. 7.

Fig. 9 is a top plan view of one of the elements of the valve located at the lower end of the strainer.

Fig. 10 is a vertical cross section of the element shown in Fig. 9.

The numeral 1 indicates the well casing which is set within the well in the manner heretofore indicated, with its lower end substantially at the upper limit of the producing formation. After this casing has been set, the hole is drilled below the lower end of the casing, as indicated by the numeral 2, so as to tap the producing formation.

The tubing 3 which may be identified as a first tubing or wash pipe is then lowered into the well and is provided at its lower end with the equipment forming the subject matter of this invention.

The coupling 4, into which the lower end of the tubing 3 is threaded, is threaded onto the upper end of a special fitting 5. Surrounding this special fitting and abutting the lower end of the collar 4, is a ring 6 serving as an abutment for the upper end of the resilient packer element 7. The lower end of this packer element 7 is received by a second abutment ring 8, similar to the ring 6.

and this ring 8 rests against a ring 9 slidably mounted upon the special fitting 5.

The ring 9 is provided with downwardly extending resilient arms 10 upon the lower ends 5 of which are carried slips 11, having upwardly facing teeth 12. The ring 9 is also provided with a lip 13 adapted to contact the projection 14 on the special fitting 5, as the ring 9 moves downwardly, whereby downward movement of the ring 10 9 will be limited.

Adjacent its lower end, special fitting 5 is formed with external left hand threads for a considerable distance, as indicated at 15, so as to receive an internally left hand threaded wedge 15 ring 16. This wedge ring has an upwardly presented outer tapered surface adapted when the wedge ring 16 is moved upwardly with respect to the special fitting 5 to contact the lower portions of the slips 11 and expand these slips.

20 The wedge ring 16 is also threaded on its outer lower portion 17 to receive the upper end of a swaged nipple 18, this nipple being prevented from disengagement with the ring 16 by means of a pin 19.

25 Below the lower end of the threaded zone 15, the special fitting 5 is provided with a smooth unthreaded zone 20, about which is disposed a packing ring 21 for the purpose of forming a seal between the lower end of the fitting 5 and 30 the interior of the swaged nipple 18. This packing ring 21 is provided with an upper abutment ring 22 in contact with the lower end of the threaded zone 15 and with a lower abutment 23 threaded to the lower end of the special fitting 35 5. This lower abutment 23 is prevented from disengagement from fitting 5 by means of a pin 24.

Upon the lower end of the swaged nipple 18, there is threaded a special coupling 25, a specially 40 formed nipple 26 being threaded into the lower end of this coupling. The lower end of the coupling 25 is formed to serve as an abutment for the upper end of a packing ring 21, the lower end of which is received by a sliding abutment ring 45 28. The sliding ring 28 rests upon the upper end 29 of a sleeve, having a hollowed out intermediate section within which are disposed a plurality of expanding dogs 30, spring pressed outwardly by means of springs 31. The lower end 32 of this 50 sleeve normally rests upon the shoulder 33 on the specially formed nipple 26.

The lower end of the nipple 26 is connected by a collar 34 to a wash pipe 35. The lower end of said wash pipe is connected by a special collar 55 36 to a valve operating fitting 37, and this special collar 36 is provided on its lower end with a seating surface 38. The valve operating member 37 is provided with splines 39 on its outer surface, each of these splines having an inclined lower end 40 a considerable distance above the lower end of the valve operating member.

When the slips 11 are expanded and the packer 7 is caused to form a seal, both of these elements engage the inner surface of a pipe section 41, 65 which may be identified as a second tubing encircling the first tubing 8 and upon the outer surface of which is wound the strainer packer 42. The upper end of the strainer packer 42 abuts against the end of a special fitting 43, threaded 70 on to the pipe section 41, and this fitting 43 is provided with a zone 44 of enlarged internal diameter just above the end of the section 41 and with the second zone 45 of reduced internal diameter above the zone 44.

75 The lower end of the packer 42 abuts against

an abutment ring 46, having a tapered and toothed portion 47 extending beneath the end of the packer. A shear pin 48 is provided for preventing downward movement of the sleeve 41 with respect to the ring 46 prior to the time that the packer 42 is to be set. The lower end of the ring 46 is recessed to receive a slip ring 49 illustrated more in detail in Figs. 7 and 8, this slip ring 49, having teeth arranged to engage the lower end of the pipe section 41 and thus support the ring 46 on the sleeve 41 during the time the device is being lowered into the well, and prevent upward movement of the sleeve 41 with respect to the ring 46 after the packer 42 has been set. This slip ring 49 holds the packer 42 in set position. The slip ring 49 is spring pressed upwardly at all times by means of the spring ring 50, better shown in Figs. 5 and 6. The lower end of the ring 46 is extended past the spring ring 50 and internally threaded at 51 to receive the swaged nipple 52. The lower end of the swaged nipple 52 is connected by means of a collar 53 to the upper end of a strainer, or screen pipe 54. To the lower end of this screen pipe is threadedly secured a valve housing 55, having an internal flange 56 adapted to receive the seat 38 on the collar 36 previously described. The valve housing 55 is internally threaded at its lower end as shown at 57 for the purpose of receiving the double valve seat member 58. A set shoe 59 is also threaded to the lower end of the valve housing 55, below the valve seat element 58.

The valve seat element 58 is provided with two transversely positioned walls or partitions 60 and 61, respectively. The upper of these partitions is provided with a perforation 62 centrally thereof, and with a plurality of additional openings 63 disposed about the center. The central opening is of a size to receive the threaded stem 64 of a valve cage element 65, this stem being secured in place by means of a nut 66 threaded on to the stem 64. Within the valve element 65, which is illustrated more in detail in Figs. 9 and 10, there is positioned a sealing ring 67. This element 65 is adapted to receive the lower portion of the valve operating fitting 37, and the splines 39 on this fitting are adapted to cooperate with the splines 68 (Figs. 9 and 10) within the upper portion of the element 65, so that a rotation of the tubing will cause a rotation of the element 65. The upper ends of the splines 68 are beveled at 69 in a manner similar to the lower ends of the splines 39 so that the fitting 37 may be lowered into place within the element 65 and the splines, in the event they happen to abut each other, will cause a slight relative rotation of the parts, so that they may interfit. The sealing ring 67 is adapted to form a fluid-tight seal between the element 65 and the fitting 37 when the two are in the position shown in Fig. 2.

The lower partition 61 of the valve seat member 58 is provided with a central opening adapted to seat a poppet valve 70, having a stem 71 slidably engaged within the guiding partition 72 of the shoe 59. This valve 70 is spring pressed upwardly toward its seated position by means of a spring 73.

The shoe 59 is provided with openings 74 in its lower end and with blades 75 which may assist in removal of obstructions during the lowering of the device into a well.

In operation, the device is made up at the surface of the well in the manner illustrated in Figs. 1 and 2, the valve operating fitting 37 occupying its position within the element 65 and the element 75

65 being so positioned that the openings 65a through the bottom thereof register with the openings 63 through the partition 60. The lower edge 38 of the collar 36 will be seated against 5 the flange 56 in the valve housing 55, and the special fitting 5 will be screwed downwardly within the wedge ring 16 until this wedge ring forces the slips 11 outwardly into engagement with the pipe section 41. When this has been done, the 10 packer 7 will be expanded into sealing engagement with the pipe section 41 and packer 21 will form a seal with the inner wall of the swaged nipple 18.

It will be noted that with the parts in the 15 position just described, the shoulder 38 on the wash pipe will rest upon the flange 56 at the lower end of the screen or strainer and that the element 46 which serves as the lower abutment for the packer 42 is positively secured to the upper 20 end of the strainer. The slips 11, on the other hand, positively secure the tubular member 41 against downward movement with respect to the wash pipe. Thus, the entire assemblage is suspended from the tubing 3 by means of the slips 25 11, the sleeve 41, and the slip ring 49, with the shear pins 48 possibly bearing some part of the weight, while the lower end of the wash pipe prevents any upward movement of the shoe 59, the strainer 54, or the abutment 46 with respect to 30 the sleeve 41. From this, it will be apparent that the abutment 46 and the element 43 cannot be moved toward each other when the parts are in the position shown in Figs. 1 and 2. Because of this, it is impossible, even though the shoe 39 35 should come in contact with a bridge as the device is being lowered into the well, for the packer 42 to be accidentally set. Neither will it be possible for a sudden jerk on the string of tubing to cause 40 the packer to set itself. Both of these eventualities are possible with the ordinary type of packer and packer suspension.

The entire structure when thus supported from the tubing 3 will be lowered into the well in the position shown in Figs. 1 and 2.

45 With the device in the lower portion of the well, washing fluid is then pumped downwardly through the tubing 3 and out through the disc valve and past the poppet valve. Thence, it will pass outwardly through the lower end of the 50 shoe 59 and upwardly about the screen to wash the walls of the well free of mud. The wash water and mud will pass upwardly outside of the screen past the packer 42 and out of the well through the casing. This mud and wash water 55 will be positively prevented from entering the screen because the screen is closed and sealed to the tubing at its upper end by means of the packer 7.

After the outside of the screen has been washed 60 sufficiently, the tubing will be rotated to the right to cause it to move upwardly with respect to the wedge ring 16 and the slips 11 and slip carrying ring 9. When the projection 14 comes in contact with the lip 13, the slips 11 will be moved away 65 from the wedge ring 16. Meanwhile, the abutment ring 8 for the packer 7 will have moved downwardly to permit the packer to retract, thus breaking the seal between the tubing and the upper end of the screen or strainer.

70 Continued rotative movement of the tubing 3 will cause the abutment ring 22 to come into contact with the shoulder at the lower end of the wedge ring 16, and as soon as this abutment ring is tightly wedged against this shoulder, the rotative movement of the tubing will be transmitted

through the wedge ring 16 and the swaged nipple 18 and thence downwardly to the valve operating member 37. Rotation of this member 37 will cause the splines 39 to engage the splines 68 and rotate the disc valve element 65 until the openings 65a therethrough are no longer in register with the openings 63, thus closing this valve. 5

It will be appreciated that pumping may be continued through the tubing and wash pipe during the release of the tubing from the pipe 41 as just described and until the rotation of the tubing causes the closing of the valve at the lower end of the strainer. When this takes place, the load on the pumps will cause them to stop, and upon raising the tubing until the element 37 is withdrawn from the packing 67, the pump will again be allowed to operate, thus indicating definitely, when the pump again starts, that the tubing has been released from the bottom hole equipment and raised from its sealed position within the shoe. If, upon raising the tubing, the pumps do not again begin to operate, the operator at the top of the well will know definitely that the tubing has not been released from the strainer and packer and that further steps must be taken. 15 20 25

As soon as the slips 11 and the packing 7 have been disengaged from the pipe section 41 and the tubing moved upwardly with respect to the pipe section 41 to disengage the valve operating fitting 37 from the element 65, further washing may take place downwardly through the tubing out the lower end of the fitting 37, and upwardly within the screen. This wash may pass upwardly between the screen and the pipe 41 on the one hand, and the tubing on the other, because of the fact that the seal 7 has now been broken. 30 35

The screen having been washed inside, the tubing will then be pulled upwardly until the lower ends of the dogs 30 pass the upper end of the pipe section 41, whereupon the dogs will be expanded by the springs 31, so that upon downward movement of the tubing 3 they will rest upon the upper end of the pipe section 41. Upon lowering the tubing so that a portion of, or all of, its weight is rested upon the pipe section 41, this pipe section will be moved downwardly to cause the shearing of the pin 48 and the lengthwise compression of the packer 42, thus expanding this packer and forming a seal between the upper end of the strainer and the interior of the casing. At the same time, when the weight of the tubing is rested upon the dogs 30, these dogs, which are mounted in the slideable sleeve 29-32, will move upwardly with respect to the tubing, thus moving the abutment ring 28 upwardly and compressing the packing 27 lengthwise, so as to cause it to form a seal between the tubing and the zone 45 of the fitting 43. 40 45 50 55

It will now be seen that all liquid entering the well from the producing formation must pass inwardly through the screen or strainer because of the fact that the upper end of the strainer is sealed to the lower end of the casing, as shown in Fig. 4. Likewise, after this liquid has passed into the interior of the screen, it must flow upwardly through the tubing only, because of the seal formed by the packing ring 27 between the tubing and the upper end of the strainer. 60 65 70

From the foregoing, it will be apparent that a means has been provided for carrying out all of the objects and advantages above set forth.

Having described my invention, I claim:

1. In a packer assembly, a pair of telescoping parts having abutments thereon, a distortable 75

5 packer element wound about said parts between said abutments, means for preventing movement of said parts away from each other, suspension means means releasably secured to the upper of said parts, and means carried by said suspension means for forming a seal between said suspension means and said upper part.

10 2. In a packer assembly, a pair of telescoping parts having abutments thereon, a distortable packer element wound about said parts between said abutments, means for preventing movement of said parts away from each other, suspension means releasably secured to the upper of said parts, and means carried by said suspension 15 means for preventing flow through said packer element about said suspension means.

20 3. In a device of the character described, in combination, a well screen, a wash pipe extending into said well screen and spaced centrally thereof and adapted to wash through the lower end thereof, a first packer means on the upper portion of said well screen for forming a seal with the wall of the well, a second packer means carried by said wash pipe for effecting a closure between said wash pipe and said screen, screen supporting means carried by said wash pipe for suspending said screen from said wash pipe, means carried by said wash pipe for expanding and contracting said second packer means into 25 and out of the sealing position and actuating said screen supporting means to suspend or disconnect the screen from said wash pipe.

30 4. In a device of the character described, in combination, a well screen, a wash pipe extending into said well screen and spaced centrally therefrom adapted to wash through the lower end thereof, a packer on the upper end of said well screen adapted to form a seal with the wall of a well, means on said wash pipe for engaging the 35 interior of said packer to suspend said packer and said screen from said wash pipe, a second packer on said wash pipe adapted to close the space and form a seal between said wash pipe and a central wall of said first packer, and means carried by 40 said wash pipe and operative to expand said second packer radially outwardly when said suspending means is in operative relation and in engagement with the central wall of said first packer.

45 5. In a device of the character described, in combination, a well screen, a first packer on the upper end of said screen for forming a seal between the upper end of said screen and the wall of a well, a tubing, a second packer element on said tubing adapted to be expanded into contact with the central wall of said first packer, first 50 operating means on said tubing adapted to coat with the central wall of said first packer for expanding said second packer element into engagement with said central wall, a third packer element on said tubing and located below said second packer element and adapted to be expanded to form a seal between said tubing and said screen after the tubing has been lifted with respect to the screen so that said second packer element is 55 above the zone of said first packer element, and second operating means carried by said tubing and adapted to engage a surface of the screen wall whereby said second operating means under downward pressure by said tubing exercises a 60 thrust lengthwise of said tubing on said third packer element to expand the latter against the inner wall of said screen.

6. In a device of the character described, in combination, a well screen, a first packer on the upper portion of said screen providing a seal between the upper portion of said screen and the wall of a well, a tubing spaced centrally from the 5 wall of the well screen, means on said tubing for coacting with said first packer to expand it into the sealing position, a second packer element on said tubing adapted to be expanded into contact with the central wall of said screen, and operating 10 means carried by said tubing and adapted to coact with the wall of said screen for expanding said second packer element into engagement with said central wall after said tubing has been lifted with respect to said screen and after said first packer 15 has been expanded.

7. In combination with a tubing for lowering a well screen into a well, a set of slips on said tubing adapted to expand and engage the upper end of said screen, an expandable sealing means about 20 said tubing above said slips adapted to be expanded by upward movement of said slips with respect to said tubing to form a seal between said tubing and the upper end of said screen, and means for expanding said slips and forcing them 25 upwardly with respect to said tubing upon rotative movement of said tubing, said means for expanding including one cam surface to engage said tubing whereby the latter may be moved lengthwise in one direction with respect to said well screen to 30 expand the slips and a second cam surface for moving said tubing in the opposite direction and thereby moving said slips to actuate expansibly said sealing means.

8. In a packer assembly, pair of telescoping 35 parts having abutments thereon, a distortable packer element wound about said telescoping parts between said abutments, means for preventing movement of said telescoping parts extensibly, a plurality of means removably bearing against 40 spaced points on said telescoping parts and engaging opposite sides of one of said telescoping parts and preventing contraction of said telescoping parts and movement of said abutments toward each other until it is desired to set the packer. 45

9. In a device of the character described, in combination, a well screen, a first packing means for forming a seal between the upper end of said screen and the walls of a well, a tubing spaced centrally from the wall of the well screen for the 50 passage of material when the screen is being washed inferiorly, means on said tubing for expanding said first packing means, second packing means carried by said tubing to form a seal between said tubing and the upper end of said screen, and means carried by said tubing to expand said second packing means after said first packing means has been expanded. 55

10. In combination with a first tubing, a packer mounted on an inner wall spaced from and encircling said first tubing, a second tubing spaced outwardly from said first tubing, a packer setting tool comprising a sleeve slidable on said first tubing, expandable dogs on said sleeve adapted to move said sleeve on said first tubing to expand and engage said second tubing to limit downward movement of said first tubing with respect to said second tubing whereby movement of said sleeve compresses said packer and the latter is expanded into sealing engagement with the inner wall of the second tubing. 60 65 70

CICERO C. BROWN.
